ATTORNEY

UNITED STATES PATENT OFFICE.

AUGUST C. KLENKE, OF BERKELEY, CALIFORNIA.

DESIGN FOR A CHILD'S VEHICLE.

59,754.

Specification for Design.

Patented Nov. 22, 1921.

Application filed December 22, 1919. Serial No. 346,801. Term of patent 3½ years.

To all whom it may concern:

Be it known that I, AUGUST C. KLENKE, a citizen of the United States, residing in the city of Berkeley, county of Alameda, State of California, have invented a new, original, and ornamental Design for a Child's Vehicle, as shown, of which the following is a specification, reference being had to the accompanying drawing, forming part thereof.

Fig. 2 is a top plan view thereof.

I claim:

The ornamental design for a child's vehicle, as shown.

AUGUST C. KLENKE
